SEAT CONSTRUCTION

William Hoffman, Philadelphia, Pa.

Application February 25, 1936, Serial No. 65,549

1 Claim. (Cl. 155—179)

My invention relates to improvements in seat constructions and particularly to spring supporting structures for upholstered furniture.

The object of my invention is to provide a cushion, or seat, having relatively greater flexibility in the center thereof than at the edge portions where undistributed weight is applied, as by a person leaning or kneeling upon the front edge portion, or upon the ends of the seat.

10 A further object is to provide a seat construction in which the compression springs which are located adjacent to the front and end portions of the seat are mounted upon relatively rigid supports and the compression springs which are 15 located adjacent to the center of the seat are supported by more yielding supporting means.

A further object is to provide slats for supporting the compression springs of the seat and form said slats of metal plate sections connected by short tension springs, and provide attaching means between the opposite ends of the slats and the seat frame.

These together with various other novel features of construction and arrangement of the parts, which will be more fully hereinafter described and claimed, constitute my invention.

Referring to the accompanying drawing, Fig. 1 is a plan view of a seat frame embodying my invention.

30 Fig. 2 is a vertical section on line 2—2, Fig. 1, and showing a completed seat.

Fig. 3 is a partial vertical section on line 3—3, Fig. 1.

In the drawing, in which like reference characters refer to like parts, 5 represents the seat 35 construction which includes a frame 6, formed of a front wall 7, a rear wall 8, and end walls 9 and 10. The walls of the frame are usually of wood, and rigidly secured together forming a 40 rectangular frame. The frame in the present disclosure is adapted for a seat for furniture, such as chairs and davenport and also as a seat for automobiles.

Horizontal slats, or strips, 12, of novel construction are mounted within the frame 6, for supporting compression springs 14. The usual upholstery material 15 and padding 16, are secured upon the springs 14. The springs 14 are secured at their upper ends by a wire structure 17, in the usual manner, as shown in Fig. 2. Said 50 springs 14 are arranged in vertical rows extending parallel with the front and rear walls 7 and 8 of the frame, as shown in Fig. 1.

The slats 12 each comprise plate sections 18 55 and 19 formed of strips of flat sheet spring

metal. Said sections are each provided with an angular end portion 22, which is bent at right angles to the length of the plate section. The end portions 22 are secured to the front and rear walls 7 and 8 of the frame by fastening devices 23, which may be in the form of staples, or split pins, which extend through the walls of the frame and are clamped upon the outer surfaces of the walls.

5 The adjacent inner ends of the plate sections 18 and 19 are connected by short tension springs 25, having end hooks 26. The plate sections are provided with holes 27 for the attachment of the hooks 26 to the adjacent plate sections.

10 The plate sections 18 and 19 are arranged with the tension springs 25 located adjacent to the center row of compression springs 14 extending parallel with the front and rear walls 7 and 8 of the frame, so that the center row of springs will be yieldingly supported and give greater flexibility to the center of the seat, as indicated by dot and dash lines in Fig. 2.

15 The plate sections 18 and 19 are of different lengths so that the tension springs 25 may be located between two compression springs 14, thus permitting the central vertical row of springs 14 to be located midway between the front and rear walls 7 and 8 of the frame.

20 The longer plate sections 18 are attached to the rear wall 8 of the frame and the shorter plate sections 19 are attached to the front wall 7 of the frame. There are two compression springs 14 secured upon each of the longer plates 18 and one compression spring 14 secured upon each of the shorter plates 19. By this arrangement the 25 compression springs 14 forming the row of springs extending through the center of the seat and parallel with the front wall 7 of the frame are more yieldingly supported than the rows of compression springs 14 located adjacent to the front and rear walls 7 and 8 of the frame.

30 Transverse plates 30 are attached by fastening devices 31 and 32 to the end walls 9 and 10 of the frame and to the longer plate sections 18 of the slats which are located next adjacent to the end walls 9 and 10 of the frame. Said plates 30 add rigidity to the slats and the compression springs located adjacent to said end walls and provide additional support for the end portions of 35 the seat.

40 The compression springs 14 are securely attached to the plate sections 18 and 19 by means of tongues 33, pressed from the metal of which the plates 18 and 19 are formed, and to which 45

tongues the bottom coils of the compression springs 14 are interlocked.

A seat construction formed with sectional slats and having the sections connected by tension springs located adjacent to the center of the seat, will have greater flexibility in the center thereof, and the edge portions of the seat will be more rigidly supported by the plate sections being directly attached to the walls of the frame.

5 10 Various changes in the arrangement and construction of the parts may be made without departing from my invention.

I claim:—

A seat construction comprising front, rear and

end walls forming a frame, compression springs located within the frame and arranged for supporting upholstery material thereon, supporting slats, said slats each comprising plate sections, means mounting the springs upon said sections, 5 means upon the front and rear walls of the frame for attaching the plate sections, tension springs connected between the adjacent ends of the plate sections, and transverse plates attached to the end walls of the frame and to the inner ends of 10 plate sections of the slats located adjacent to and parallel with the end walls of the frame.

WILLIAM HOFFMAN.
